(57) **CLAIM**

The ornamental design for a ball point pen, as shown and described.

DESCRIPTION

FIG. 1 is a perspective view of the new design for a ball point pen;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof; and,

FIG. 8 is a right side view of the ball point pen shown in FIG. 1 in an alternate configuration, having the cap coupled at the bottom of the ball point pen, the left side view being a mirror image thereof.

The oblique line shading represents a transparent surface.

1 Claim, 8 Drawing Sheets
